CIGARETTE

Walter C. Higley, Toledo, Ohio

Application February 21, 1936, Serial No. 65,119

5 Claims. (Cl. 131—52)

The present invention relates to new and useful improvements in cigarettes and has for its primary object to provide, in a manner as hereinafter set forth, a cigarette which will be self-lighting.

Another very important object of the invention is to provide a self-lighting cigarette embodying novel means for closing and sealing one end of the article in a manner to prevent the 10 igniting head from being damped by moisture from the tobacco.

Another important object of the invention is to provide a self-lighting cigarette embodying novel means for mounting the igniting head 15 thereon.

Other objects of the invention are to provide a self-lighting cigarette which will be comparatively simple in construction, attractive in appearance and which may be manufactured at low 20 cost.

All of the foregoing and still further objects and advantages of the invention will become apparent from a study of the following specification, taken in connection with the accompanying 25 drawing wherein like characters of reference designate corresponding parts throughout the several views, and wherein:—

Figure 1 is a view in side elevation of a cigarette constructed in accordance with the present 30 invention.

Figure 2 is an elevational view of an end portion of the cigarette, showing the head carrying element detached therefrom.

Figure 3 is an elevational view, taken at right angles to Figures 1 and 2, and showing the cigarette before the head is applied.

Figure 4 is a view in side elevation of an end portion of the cigarette, showing the head and the carrying element therefor in vertical section.

Figure 5 is a view in end elevation, showing the tip of the cigarette before the head is applied.

Figure 6 is a fragmentary view in side elevation of a modified form of the invention.

Figure 7 is a view similar to Figure 6 but showing the head in vertical section.

Figure 8 is a detail view in side elevation of another modification, showing the head in vertical section.

Figure 9 is a bottom plan view of the invention 50 as shown in Fig. 3.

Referring now to the drawing in detail, it will be seen that the reference numeral 1 designates generally the cigarette, said cigarette including a paper wrapper 2. At one end portion, the substantially tubular paper wrapper 2 is folded or

tucked inwardly on diametrically opposite sides, as at 3, in a manner to provide a tapered tip 4 the free end of which is substantially N-shaped, as at 5 (see Figure 5). After the tip 4 is thus formed it is dipped in wax for sealing the cigarette at this end to prevent the passage of moisture from the tobacco.

It will be noted that the tip 4 is so formed as to provide substantially flat opposite side walls 6. Secured by an adhesive on the tip 4 and projecting from the free end thereof is a substantially Y-shaped head carrying element 7. The element 7 is formed from a strip of heavy paper folded upon itself in a manner to provide legs 8 which straddle the tip 4 and which are secured to the substantially flat sides 6 of said tip. After the tip 7 is applied said tip is dipped in a suitable combustible material in a manner to form an ignitable head 9 thereon.

In the modification shown in Figures 6 and 7 of the drawing the element 7 is omitted and an ignitable head 10 is applied directly to the free end portion of the tip 4.

In the Figure 8 modification a separate tip 11 of "Cellophane" or other suitable water resisting material is applied to one end portion of the cigarette 1. This tip 11 is folded or formed in a manner similar to the tip 4 and an ignitable head 12 is applied to the free end portion thereof. If desired, the element 7 may be applied to the 30 tip 11 for carrying the head 12.

It is believed that the many advantages of a cigarette constructed in accordance with the present invention will be readily understood, and although preferred embodiments of the invention 35 are as illustrated and described, it is to be understood that further modifications and changes in the details of construction may be resorted to which will fall within the scope of the invention as claimed.

What is claimed is:—

1. A cigarette comprising a wrapper, one end portion of said wrapper including inwardly tucked opposite side portions forming a substantially tapered tip, and an ignitable head on the 45 free end portion of said tip.

2. A cigarette comprising a substantially tapered tip on one end, a substantially Y-shaped element straddling said tip and secured thereto, said element projecting from the free end of the 50 tip, and an ignitable head on the projecting portion of the element.

3. A cigarette comprising a wrapper, one end portion of said wrapper including inwardly tucked portions providing a substantially tapered 55

tip including a substantially N-shaped end, and an ignitable head mounted on the free end portion of said tip.

4. A cigarette comprising a substantially tapered tip on one end including substantially flat sides, a substantially Y-shaped element straddling said tip and including diverging legs secured to the flat sides thereof, said element projecting beyond the free end of the tip, and an ignitable head on the projecting portion of said element.

5. A cigarette comprising a wrapper, one end

portion of said wrapper including inwardly tucked portions providing a substantially tapered tip including a substantially N-shaped end, said tip further including substantially flat side portions, a substantially U-shaped element straddling the tip and including diverging legs secured to said substantially flat side portions, said element projecting from the free end of the tip, and an ignitable head on the projecting portion of the element.

WALTER C. HIGLEY.
